(57) **CLAIM**

The ornamental design for a rocking chair carriage assembly, as shown and described.

DESCRIPTION

FIG. 1 is a perspective view of the rocking chair carriage assembly of the invention;

FIG. 2 is a front view of the rocking chair carriage assembly illustrated in FIG. 1;

FIG. 3 is a side view of the rocking chair carriage assembly illustrated in FIG. 1;

FIG. 4 is a top view of the rocking chair carriage assembly illustrated in FIG. 1;

FIG. 5 is a bottom view of the rocking chair carriage assembly illustrated in FIG. 1;

FIG. 6 is a rear view of the rocking chair carriage assembly illustrated in FIG. 1; and,

FIG. 7 is a second perspective view of the rocking chair carriage assembly illustrated in FIG. 1.
